UNITED STATES PATENT OFFICE.

SAMUEL JAMES COX, OF LONDON, ENGLAND, ASSIGNOR TO CINECHROME INSTRUMENTS, LIMITED, OF LONDON, ENGLAND.

CINEMATOGRAPHY.

Application filed October 20, 1923, Serial No. 669,840, and in Great Britain October 24, 1922.

The present invention relates to improvements in and relating to cinematography in which use is made of a wide film, and being particularly applicable to that aspect of two colour cinematography in which a double-width film is used, each pair of positive pictures across the width of the film being monochrome renderings by colour selection, which when projected for superimposition on the screen, simulate or give a suggestion or partial rendering of the "colours of nature" when the projection is through appropriately coloured light-filters, it will be hereinafter described in that application.

Hitherto the projection has been open to the objection that a defect known as colour-fringing is from time to time manifested by the appearance of bright flashing or changing marginal colours, this being frequently for lack of a steady or straight run of the medial line of the film along a line which is medial to the two elements of the double gate of the projector. Or, in other words, and somewhat more loosely, the film should run truly and steadily to the double gate and to the pair of lenses.

The above mentioned colour fringing often arises pronouncedly when the positive film is printed from a composite negative film, or made from various positive portions, the negatives of which have been exposed in different cameras, and/or when the shrinkage has been unequal owing to peculiarities of the film base or to varying conditions of time, temperature, or storage.

When such composite and irregular bands of negative film are printed, guidance from or by an edge piece (or edge pieces) at the double gate becomes unsatisfactory, and in tolerable colour-fringing steps in with respect to some portions when the positive film is projected with its appropriate colour screening.

The present invention overcomes this disadvantage by promoting registration, and reducing, eliminating, or avoiding the colour-fringing, or lack of registration.

To this end, the present invention broadly consists in means for giving positive guidance to the film along the assumed medial line or imaginary equator between the two series of colour selection or other pictures in place of the false or imperfect guidance from

a side guide to the gating area, or of dependence on the driving organs for medializing.

In order that the present invention may be the more readily understood reference is had to the accompanying drawings, which illustrate, by way of example only, a construction for medial guidance thereunder which has been found to work well in relation to intermittent-moving printing machines.

In the drawings:

Fig. 1 shows a piece of double width film having a medial rank of perforations for the purpose described between the usual two driving rows of perforations at the edges.

Figs. 2 and 3 are front and side views respectively of the feed and other mechanism mount of a two colour printer incorporating a guiding or registering device according to the present invention.

To carry this medial guidance into practical effect, there is made in the double-width film *a* midway or thereabouts between the two usual driving-rows of perforations *b*, *c* at the edges, a medial rank or row of perforations *d*, which, while leading the film to the gate, come into action with a series of tapering organs which, at a flaccid part of the film, advance through the perforations in sequence and finally fit well into or contact to a fit with the ends or sides of the perforations *d*, to give to the film the correct medial set or position at the gate aperture. By ends or sides are meant those bounding edges of the perforations in the direction of the run of the film as distinguished from the tops or bottoms which are at right angles to the direction of the run of the film.

These medial or extra perforations *d* may be denominated the equating perforations to distinguish them from the usual marginal perforations *b*, *c* which serve for driving or traction purposes, and also from the medial row of perforations in a wide film used for traction purposes.

A working example of a double width film suited to run on a long sprocket which is also adapted to take the ordinary standard or single width film is shown full size in Fig. 1, and illustrates a scale and shape for the equating perforations which has given good results, that is to say, the length of an equating perforation is as great as the

space between the pictures conveniently allows, which in general for ordinary purposes will at least equal in width a standard $\frac{1}{16}$ " pressure guide margin, and the height, or dimension in the direction of the run of the film is less than the length; very approximately half. Further the ends of the equating perforations are not straight but arched.

10. While the film is being led into the gate aperture, it is positively guided by the tapering organs into the correct medial set or position as stated above. A fit or grip of a pointed organ (or steady pin) on the long 15 sides of the perforations, or top and bottom is not desirable.

A working example of steady pin guidance which serves well for the purposes of the present invention is depicted in Figs. 20 2 and 3, being as preferred that it should be a tapering rectangular tooth of an idling sprocket *e* mounted over and near the double printing gate *f* and gearing into the row of equating perforations *d*, the sprocket *e* being idle as to rotation but firmly mounted as shewn in Fig. 2 against endwise or sidewise motion and firm against flexions like the flexions of a circular saw.

The double-width negative and positive 30 films *g*, *h*, travel from their appertaining spools under a guide roller *i* between the sprocket *g'* and pressure or bolster rollers *g²*, *g³*, thence, after looping, between the idling sprocket *e* and pressure or bolster 35 roller *e'* and through the printing gate *f*, being clawed down intermittently by suitable claw mechanism not shewn. From the printing gate *f* the films travel over a bottom sprocket not shewn and are wound on 40 spools, or, alternatively the printed positive may be passed directly into the developing apparatus.

All parts of the printer not shewn are 45 readily understood by those versed in the art.

The course of the films is indicated by the Morse line *j*, dash line *k*, and full line *l*.

When the idling sprocket *e* is used, it is 50 obvious that a plurality of teeth must gear into the equating perforations *d* so that various similar steady pins or a plurality thereof, for example, two, depending on the wrap of the film, come into the final or culminating position in sequence. In order to facilitate 55 the entry and leaving of the teeth which act as steady pins there should not be too much wrap of the film on the idling sprocket. A four teeth wrap as shewn in Fig. 3 gives good results, two teeth being in the final or culminating position at the same time.

60 By the term steady pin when used in reference to the pointed organ or a tooth of the idling sprocket is to be understood a pin that is steady in relation to a transverse movement of the strip of film.

While the medial guidance of the double width film may be effected in the camera, in the printer or in the projector or in any similar or like device or apparatus having a multiple function, as in all cases the present invention conduces to steadiness and good register, the present invention is of special importance in relation to the printer as already explained. 70

In the printer the device according to the present invention not only brings each pair of negative pictures into register with the positive film by common reference to a medial perforation but it more or less perfectly equates and averages differences in width 80 arising from the causes previously mentioned. 75

Thus what would otherwise be intolerable colour fringing or want of register is brought to something which is relatively unimportant. 85

It is to be noted that all film stock for use in relation to the present invention is similarly perforated, whether for positive or negative. 90

Although we have spoken in the chosen example of the generally preferred intermittent moving apparatus, the herein described system of retaining a broad or two picture film of the kind described approximately medial and true to path may be incorporated in continuously moving apparatus and such an application is to be regarded as forming part of the present invention and included in the claims hereof. 95 100

The invention is also available in relation to other broad films than colour films of the kind described, for example, broad cinematographic films for the production of stereoscopic effects, where it is desirable to promote steady running and true registration. 105

It is not essential for the purposes of the present invention to provide the films with the usual driving rows of perforations as these may be replaced by rows of clearing holes, or in some cases dispensed with altogether, and use made of the medial rank or row of equating perforations for driving or traction purposes as well as for medially setting or positioning purposes, appropriate feed mechanism being of course provided. 110 115

One advantage of a film medially perforated midway between the edges is that it can be threaded up in reverse aspect if a back projection is desired to be made. 120

What I claim is:—

1. In and in connection with broad cinematographic films of the kind described, the combination for promoting steady running and true registration of a broad film, or two such films, embodying a series of tapering organs or "steady" pins and a medial rank of equating perforations so formed, arranged and operating that while the film or films are being led to the gate aperture the 125 130

film or films are positively guided by the "steady" pins into the correct medial set or position substantially as and for the purposes described.

- 5 2 Means for retaining a broad film or two such films of the kind described approximately medial and true to path in a cinematographic apparatus, comprising a rank of equating perforations in the film 10 and an idling sprocket in said apparatus
- gearing with said perforations, the teeth of said idling sprocket being of a width so as to engage with the shorter dimension sides of the appropriate perforations while the film, or two such films, is or are being led 15 to the gate aperture, for the purposes described.

In testimony whereof, I affix my signature.

SAMUEL JAMES COX.
